(57) **CLAIM**

I claim the ornamental design for a footstool with exposed table plate, as shown.

DESCRIPTION

FIG. 1 is a front left perspective view for a footstool with exposed table plate of my design;

FIG. 2 is a front right perspective view thereof;

FIG. 3 is a rear left perspective view thereof;

FIG. 4 is a rear right perspective view thereof;

FIG. 5 is a front elevational view thereof;

FIG. 6 is a rear elevational view thereof;

FIG. 7 is a top view thereof;

FIG. 8 is a bottom view thereof; and,

FIG. 9 is a left side elevational view thereof, the right side being a mirror image.

The dotted lines represent stitched seams that are part of the design.
